LADY'S STOCKING

Melvin A. Rickert, Lambertville, N. J., assignor to Amwell Full Fashioned Hosiery Company,
Inc., Lambertville, N. J.

Application January 7, 1953, Serial No. 23,052

Term of patent 14 years

(Cl. D47—7)

To all whom it may concern:

Be it known that I, Melvin A. Rickert, a citizen of the United States, residing at Lambertville, county of Hunterdon, State of New Jersey, have invented a new, original, and ornamental Design for a Lady's Stocking, of which the following is a specification, reference being had to the accompanying drawing, forming a part thereof.

I claim:

The ornamental design for a lady's stocking, as shown.

MELVIN A. RICKERT.
